UNITED STATES PATENT OFFICE.

DAVIS N. SMITH, OF DECATUR, TENNESSEE, ASSIGNOR OF ONE-HALF TO
JESSE H. GUINN, OF DECATUR, TENNESSEE.

ALARM.

SPECIFICATION forming part of Letters Patent No. 772,480, dated October 18, 1904.

Application filed November 21, 1903, Serial No. 182,175. (No model.)

To all whom it may concern:

Be it known that I, DAVIS N. SMITH, a citizen of the United States, residing at Decatur, in the county of Meigs and State of Tennessee, have invented a new and useful Alarm, of which the following is a specification.

This invention relates to an improved burglar-alarm, and has for its object to provide a simple, inexpensive, and efficient device of 10 the character adapted for ready attachment to a door or a window and so arranged as to sound an alarm when an attempt is made to open the door or raise the window.

A further object of the invention is to provide an alarm, the relative disposition of the 15 several parts being such that when the door or window is opened a cap, cartridge, or similar detonating compound will be exploded and at the same time cause a match to be automatically lighted.

The invention consists in the construction and novel combination and arrangement of parts hereinafter fully described, illustrated in the accompanying drawings, and pointed 25 out in the claims hereto appended, it being understood that various changes in form, proportion, and minor details of construction may be resorted to without departing from the principle or sacrificing any of the advantages of this invention.

In the accompanying drawings, Figure 1 is a perspective view of a portion of a door, showing a burglar-alarm constructed in accordance with my invention applied thereto. Fig. 2 is 35 a longitudinal sectional view of the same. Fig. 3 is a transverse sectional view on the line 3 3 of Fig. 2. Fig. 4 is a perspective view illustrating a modified form of the invention.

Similar numerals of reference indicate corresponding parts in all the figures of the drawings.

1 designates a door adapted to open inwardly, 2 the door-frame, and 3 my improved 45 burglar-alarm.

The alarm consists of a frame or casing, preferably rectangular in shape, as shown, and comprising a pair of spaced longitudinal side bars or plates 4, between the opposite

ends of which are riveted or otherwise secured angularly-disposed arms 5 and 6. The arms 5 and 6 are preferably arranged at right angles to each other and provided with one or more openings adapted to receive thumbscrews or similar fastening devices 7, by 50 means of which the alarm is secured in position on the door-frame. Pivoted between the side bars 4 of the frame is a hammer 8, provided with an arm or extension 9, the end of which is bifurcated, as shown 55 at 10, said hammer being adapted to explode a cap or cartridge placed on a nipple or tube 12, preferably formed integral with a longitudinal spacing-block 13, secured in any suitable manner between the side bars of the 60 frame. Pivoted between the bifurcated ends of the extension 9 is a link 14, the opposite end of which is pivotally connected to a flat spring 15, secured to the frame at a point adjacent the arm 5, said spring being adapted to 65 throw the hammer forward in contact with the nipple 12 when the former is released. As a means for setting the hammer I provide 70 a pivoted trigger-bar 16, the forward end of which is adapted to engage a shoulder 17, 75 formed in the pivoted end of the hammer, said trigger-bar being held in engagement with the shoulder when the hammer is cocked by means of a spring 18, mounted in grooves or channels 19 in the fixed end of the arm 6. One end of the trigger-bar 16 is provided 80 with a flat disk-shaped head 20, upon which is revolvably mounted a correspondingly-shaped trigger 21, the end of which extends in the path of the door or sash, so that when 85 the door or sash is opened the trigger-bar will be depressed, releasing the hammer and causing the same to explode the cap or cartridge, and thereby sound the alarm.

The lower portion of the side bars 4 are recessed, as shown at 22, so that the trigger 21 will lie in substantially the same plane with the frame, thereby permitting said frame to fit flush against the door-casing when the alarm is in position, as clearly shown in Fig. 95 1 of the drawings.

The block 13 is provided with one or more openings 22', adapted to receive the cylin-

drical shank 23 of a preferably curved arm 24, the face of which is roughened or provided with a strip of sandpaper or similar abrasive material 25. A match 26 is inserted in a 5 longitudinal opening 27 in the hammer 8, said match being adapted to be ignited by frictional contact with the roughened face of the arm 24 when the hammer is released.

By the term "match" I wish it understood 10 that I mean any inflammable or combustible material capable of being ignited by contact with a roughened or otherwise specially-prepared surface.

In practice the alarm is preferably placed 15 against the lower portion of the inside door-frame, with the arm 6 in contact with the floor and the trigger extending in the path of the door, as clearly shown in Fig. 1 of the drawings, being secured in such position by 20 means of the screws 7. Should a person attempt to open the door in the direction of the arrow indicated in Fig. 1, it will cause the trigger 21 to depress the trigger-bar 16, releasing the hammer and causing the same to 25 explode the cap or cartridge. As the hammer descends the head of the match will contact with the arm 24, thereby igniting the same. The door may be opened or shut without operating the alarm by turning the trigger 30 to one side and out of contact with said door, or, if desired, the alarm may be quickly detached by removing the screws, as will be readily understood.

In Fig. 4 I have shown a modified form of 35 the invention, in which the head of the hammer 8 is provided with transversely-disposed openings 27', adapted to receive the matches 28, said matches being ignited as the hammer descends by contact with obliquely-disposed 40 arms 29, secured on either side of the side bars of the frame. The trigger is also provided with an elongated opening or slot 30, by means of which said trigger may be moved in a horizontal plane to either side of the 45 frame.

From the foregoing description it will be seen I have provided an extremely simple and effective alarm capable of being manufactured at a small cost and being of such small size 50 and compact arrangement may be readily removed and carried about in the pocket.

While I have shown the alarm attached to

the lower portion of the door-frame, it is obvious the same may be attached at any convenient position thereon, the device being 55 also applicable to windows, shutters, and the like.

Having thus described the invention, what is claimed is—

1. In an alarm, a frame having angularly-disposed supporting-arms, means carried by the frame for supporting a detonator, a spring-actuated hammer for striking the same, a match carried by the hammer, a pivoted trigger-bar for locking the hammer, a trigger 65 pivoted to the trigger-bar and adapted to be swung into and out of operative position, and a match-igniter mounted on the frame and arranged in the path of the hammer.

2. In an alarm, a frame comprising a pair 70 of spaced longitudinal plates, supporting-arms secured to the opposite ends of the frame and arranged at right angles to each other, means carried by the frame for supporting a detonator, a pivoted hammer for striking the same, a spring secured to the frame, a pivotal connection between the spring and the hammer, a match carried by said hammer, a match-igniter mounted on the frame, a spring-pressed trigger-bar for locking the hammer, 75 and a trigger pivoted to the trigger-bar and adapted to be swung into and out of the path of a movable door or sash for releasing the hammer.

3. In an alarm, a frame comprising a pair 80 of spaced longitudinal plates provided with aligned terminal slots or recesses, means carried by the frame for supporting a detonator, a spring-actuated hammer for striking the same, said hammer being provided with an 90 opening for the reception of a match, a trigger-bar pivoted to the frame for locking the hammer, a trigger pivoted to the trigger-bar and adapted to engage the terminal slots when 95 said trigger is in the inoperative position, and a match-igniter mounted on the frame and adjustable with relation to the hammer.

In testimony that I claim the foregoing as my own I have hereto affixed my signature in the presence of two witnesses:

DAVIS N. SMITH.
